UNITED STATES PATENT OFFICE.

JOHN P. TOBIN, OF SAN FRANCISCO, CALIFORNIA.

DESIGN FOR AN ORGAN OR PIANO CASE.

No. 39,780.

Specification for Design.

Patented Jan. 26, 1909.

Application filed October 22, 1908. Serial No. 459,105. Term of patent 7 years.

To all whom it may concern:

Be it known that I, JOHN P. TOBIN, residing in the city and county of San Francisco,

State of California, have invented a new, original, and ornamental Design for Organ or Piano Cases, of which the following is a specification, reference being had to the accompanying drawing, forming part thereof.

The figure is a perspective of my new design.

I claim:

The ornamental design for an organ or piano case, as shown.

JOHN P. TOBIN.
